UNITED STATES PATENT OFFICE

171,473

CABINET FOR A HEATER OR THE LIKE

Lawrence H. Wilson, Detroit, Mich., assignor to
Motor Wheel Corporation, Lansing, Mich., a
corporation of Michigan

Application May 21, 1952, Serial No. 19,805

Term of patent 7 years

(Cl. D81—19)

To all whom it may concern:

Be it known that I, Lawrence H. Wilson, a citizen of the United States, residing at Detroit, in the county of Wayne and State of Michigan, have invented a new, original, and ornamental Design for a Cabinet for a Heater or the like, of which the following is a specification, reference being made to the accompanying drawings, forming part thereof.

Fig. 1 is a perspective view of a cabinet for a heater or the like, showing my new design.

Fig. 2 is a section along the line 2—2 of Fig. 1.

Fig. 3 is a fragmentary sectional view along the line 3—3 of Fig. 1.

Fig. 4 is a fragmentary detail of the cabinet top grille.

Figs. 5 and 6 are sections along the lines 5—5 and 6—6, respectively, of Fig. 4.

Fig. 7 is a section along the line 7—7 of Fig. 1.

The side of the cabinet not shown is substantially the same as the side shown and the back of the cabinet is plain.

I claim:

The ornamental design for a cabinet for a heater or the like, substantially as shown and described.

LAWRENCE H. WILSON.
